UNITED STATES PATENT OFFICE

2,660,140

VIBRATION ISOLATING MEANS FOR
SEWING UNITS

John G. Attwood, Oak Park, Ill., assignor to
Union Special Machine Company, Chicago, Ill.,
a corporation of Illinois

Application May 18, 1950, Serial No. 162,783

11 Claims. (Cl. 112—258)

1

This invention relates to a sewing unit involving a pedestal type support carrying a sewing machine and its individual driving motor. It relates particularly to such a unit in which the sewing machine is of the feed-off-the-arm type, the work arm being spaced a substantial distance from any of the supporting structure of the unit, so that the work may be freely manipulated in applying it to and removing it from the work arm. The invention is, however, applicable also to units having sewing machines of other types.

Units of the character indicated, as heretofore constructed, have been highly satisfactory from most standpoints, but they have had a tendency to set up excessive vibrations when the sewing machines have been operated at high speeds. Such vibration creates noise and is otherwise objectionable to the operator. At times it interferes with the proper functioning of the machine. Prior attempts to eliminate such vibration have been only partially successful.

A primary object of this invention has been to provide a sewing unit of the foregoing character which may be operated at high speed without objectionable vibration. Toward this end a novel arrangement has been provided for mounting the sewing machine and the driving motor on the pedestal support.

Other objects, features, and advantages of the invention will appear from the detailed description of an illustrative form of the same which will now be given in conjunction with the accompanying drawings, in which:

Fig. 1 is a side elevational view of a sewing unit embodying the invention, a cover member for the driving motor being indicated in broken lines;

Fig. 2 is an enlarged detail view of certain of the parts in vertical section along the line 2—2 of Fig. 1;

Fig. 3 is a top plan view of the sewing unit with the cover member removed from the driving motor;

Fig. 4 is an enlarged detail view, in vertical section taken along the line 4—4 of Fig. 1, showing the means for securing the driving motor;

Fig. 5 is a view, partially in plan and partially in horizontal section, showing the base portion of the pedestal support;

Fig. 6 is a detail view, partly in elevation and partly in vertical section, showing the means for supporting the sewing machine and various connected devices;

Fig. 7 is a detail view, partly in plan and partly in section, showing a handwheel associated with the motor drive;

2

Fig. 8 is a detail view, in perspective, of a plate member forming part of the supporting structure, a portion of the plate being broken away;

Fig. 9 is a horizontal sectional view through the cover member for the motor drive, the latter being omitted to disclose the supporting structure beneath the cover;

Fig. 10 is a side elevational view of the supporting structure at the upper end of the vertical column of the pedestal and the cover for the driving motor;

Fig. 11 is a detail view, partly in elevation and partly in section, showing one of the means for retaining the cover for the driving motor;

Fig. 12 is a plan view of a horizontal bracket member forming part of the pedestal support;

Fig. 13 and Fig. 14 are side and end elevational views, respectively, of a modified form of the support plate shown in Fig. 8; and

Fig. 15 is an enlarged detail view, partly in section of a type of bolt member employed to isolate vibrations.

Referring now to the drawings, the main supporting structure is in the nature of a pedestal comprising a base member 10 having on its underside a plurality of appropriate foot-like projections for engaging the floor. An upwardly extending sleeve 11 adjacent one end of the base member is arranged to receive the lower end of a tubular column 12 which is secured within the sleeve 11 by suitable set screws 13. At the upper end of the column 12 there is similarly mounted a bracket member 14, having a collar portion secured to the column by set screws 15 and having a horizontally disposed, relatively flat portion arranged to support the parts to be hereinafter described. The form of the bracket arm 14 is best illustrated in Fig. 12, in plan, and in Figs. 1 and 10 in elevation. The vertical position of the bracket member in relation to the floor may be varied slightly by adjusting the position of the column 12 both in relation to the sleeve 11 and to the collar portion of the bracket arm.

On the upper surface of the bracket member 14 there is mounted a plate member 16 which is secured to member 14 by a plurality of bolt members 17. Six such bolt members are shown in Figs. 3 and 8. Each is of the form disclosed in Figs. 6 and 15. It comprises an upwardly extending element 17a which passes through a suitable opening 18 through the plate and a downwardly extending element 17b which passes through an opening 19 extending through the top portion of the bracket member 14. The elements 17a and 17b are provided with enlarged heads 17c

3

and 17d, respectively, which are firmly embedded in and held in assembled but spaced relation by means of an encasing cylindrical element 17e formed of a suitable vibration absorbing material, which is relatively soft and capable of yielding. It may suitably be formed of compressed felt or rubber or synthetic resin or the like. Element 17e is seated in suitable counterbores in the under surface of member 16 and the upper surface of member 14. A nut 20 applied to the upper end of the element 17a retains a washer 21 in firm engagement with the upper surface of the plate 16. A nut 23 applied to the element 17b similarly retains a washer 24 firmly against the under surface of the horizontal portion of member 14 to complete the assembly and retain the members 14 and 16 in firmly united relation. The vibration absorbing elements 17e serve to absorb and prevent the transmission to the bracket member 14 of any vibrations imparted to the plate 16. It has been found that the provision of a plurality of such elements in the manner indicated, between two relatively flat plate-like members, is exceptionally effective for the elimination of noise and vibration.

To assist further in eliminating vibration of the supporting structure as a whole the plate 16 is made relatively thick in the region of the outer end of the bracket member 14. The thickened portion of the plate is indicated at 25 in Figs. 3 and 6. If desired, the plate may be thickened to an even greater extent in this area, as indicated in Figs. 10, 13 and 14. Thus a downward bulge may be provided on the under surface of the plate in substantially the same region in which an upward bulge is provided on its upper surface. When this is done the thickened portion of the plate on its underside should be cut away slightly, as indicated at 25a in Fig. 9, to accommodate the outer end of the bracket member 14.

At its right end (Figs. 3, 9 and 13), the plate 16 extends laterally to form a reverse L-shape. The outer end of the laterally extending branch of the L projects downwardly, as shown at 26 in Figs. 6, 13 and 14, to provide a vertically disposed portion spaced slightly from a face 27 of the bracket member 14. Against an outer flat surface 28 of extension 26 is abutted a corresponding flat surface on the main frame 29 of the sewing machine forming part of the unit. A series of openings 30 extending through the portion 26 of plate member 16 are arranged to receive screws 31 which have threaded engagement with openings 32 in the adjacent wall of the sewing machine frame 29. A firm connection is thus provided between the sewing machine frame and the plate 16 and these parts may have metal to metal contact in view of the isolation, by means of the elements 17e, of any vibrations developed by the sewing machine.

As best shown in Figs. 1 and 3, the sewing machine frame 29 comprises an upper horizontally disposed portion 33, a downwardly extending portion 34, and a free-ended work supporting arm 35 which projects from the lower end of portion 34 at an angle to a vertical plane extending through the axis of the part 33 of the frame. The outer end of the work supporting arm 35 terminates beneath a needle head 36 which projects laterally from the adjacent end of the part 33. The construction of the sewing machine is generally similar to that disclosed in the Christensen et al. Patent No. 1,741,095, granted on December 24, 1929, and in modified form in Sauer Patent No. 2,474,331, granted on June 28, 1949. Since the

4

details of construction and operation of the sewing machine form no part of the present invention, it is unnecessary to describe them more fully. A main operating shaft extends longitudinally of the portion 33 of the frame, as disclosed in said prior patents, and this carries at its outer end, which projects from the frame, a pulley 37.

Mounted on the upper surface of the plate 16 is an electric drive unit 38 comprising a motor 39 and a clutch 40. This power unit may be of the same general construction as the unit disclosed in the patent to Peets et al., No. 2,004,055, granted on June 4, 1935. It involves an axially slidable sleeve carrying a shaft on which is mounted one member of a friction clutch and on which is also mounted a pulley 41 connected by a belt 42 with the pulley 37 of the sewing machine. As best shown in Fig. 7, the pulley 41 is splined to the end of the driven shaft 43 of the clutch. This shaft, however, is provided with a screw threaded portion 44, extending beyond the outer face of the pulley 41, which carries an internally threaded portion 45 of a sleeve-like extension 46 of a handwheel 47. This handwheel is so positioned as to be readily accessible to the operator and eliminates the inconvenience of turning a combined handwheel and pulley, normally provided in the position of the pulley 37, for turning the main drive shaft of the sewing machine by hand.

In order to permit adjustment of the power unit in relation to the plate member 16, for belt tightening purposes, elongated openings 48 are provided through the plate member (see Figs. 4, 8 and 9). These openings are arranged to receive bolts 49 having enlarged heads 50 cooperating with the under surface of the plate member adjacent the openings. Each bolt has a nut 51, in threaded engagement with its upper end, arranged to be screwed tightly against a sleeve 52 which surrounds the bolt and at its lower end engages the upper surface of the plate member 16. Surrounding the sleeve 52 is a vibration absorbing sleeve 53 formed in two parts, upper and lower, of rubber or felt or other yielding material. Each of the parts of sleeve 53 has an outwardly extending flange arranged to cooperate with one of the faces of a foot 54 formed on the frame of the driving unit. Washers 55 are preferably provided at the outer ends of the sleeve 53. The arrangement is such that when the nut 51 is tightened against the upper end of the sleeve 52, the flanges of the sleeve 53 will be squeezed sufficiently to retain the driving unit firmly in its set position. It will be understood that when it is desired to adjust the driving unit in relation to plate member 16, the nuts 51 are loosened and the bolts 49 are caused to slide in one direction or the other along the openings 48. Upon tightening of the nuts 51 the power unit is firmly secured to the plate member 16 again. If desired, the vibration isolating elements 53 and the sleeve 52 may be omitted, since it has been found that the elements 17e serve quite effectively to isolate any vibration imparted to the supporting plate 16, whether derived from the sewing machine or the power unit. It is, however, preferred to eliminate the transmission of vibrations from the driving unit to the plate by the use of the sleeves.

In the base 10 a pair of treadles 56 and 57 is provided for controlling various functions of the unit. Treadle 56, for example, is adapted to lift the presser bar of the sewing machine, whenever desired, through connections to be hereinafter

described. Treadle 57 is arranged to control the clutch of the power unit to determine at will when the sewing machine is to be driven. Suitable connections from this treadle are also provided for operating a pump arranged to transfer lubricant from certain points to others within the sewing machine frame, as will be explained hereinafter.

Referring to Fig. 5, the treadle 57 has downwardly extending supporting ears clamped to a rock shaft 58 suitably journaled in the base 10. The left end of this rock shaft is bent at right angles, as indicated at 59, and extends to a point beneath the lower end of the column 12. Here it is connected with a rod 60 which extends upwardly through the column. In a similar manner the treadle 56, which is pivoted on the base member by means of a pin 61, carries a rod 62 adjacent its opposite end which extends to a point beneath the lower end of the column 12. Here it is connected with a rod 63 extending upwardly through the column.

Rod 60 has its upper end coupled by means of a block 60b with a parallel rod 60a (Fig. 1). The latter is connected with the free outer end of a yoke 64 (Figs. 1 and 3) having a split collar 65 (Figs. 1 and 6) arranged to be clamped upon the inner end of a sleeve 66 forming part of the clutch of the power unit. As will be seen by reference to the Peets, et al. patent, above mentioned, rocking of the sleeve 66 by a downward pull on the arm of yoke 64 will cause the sleeve to be shifted axially to engage the clutch and cause the pulley 41 to be driven. The connection between the yoke 64 and the rod 60a preferably includes a ring 67 secured to the yoke and extending inwardly therefrom. Rod 60a passes upwardly through this ring and carries a collar 68 cooperating with the under face of the ring. A spring 69 is compressed between the upper face of the ring and a washer 70 carried by the rod 60a and held thereon by an enlargement of the upper end thereof. It will be seen that in this way the arm 64 is normally held against the collar 68 but as the rod 60a is moved downwardly the yoke 64 is yieldingly urged downwardly but is not positively forced in this direction. After the clutch has been engaged the further movement of the treadle and corresponding downward movement of the rods 60, 60a serves to compress the spring 69 to increase the pressure between the clutch faces. A spring 71 (Fig. 6), connected at one end with a rearwardly extending arm integral with the split collar 65 and at its other end with a hook or the like carried by the frame of the power unit, serves normally to rock the sleeve 66 and yoke 64 into their inactive positions in which the clutch elements are disengaged.

Another arm 72 (Figs. 1, 3 and 6) of the yoke 64 is connected, through means now to be described, with a lubricant pump. A vertically disposed opening through the arm 72 slidably receives a pin 73 which carries a pair of centering springs 74. These cooperate at their inner ends with the opposite faces of the arm 72 and at their outer ends with collars 73a secured to the pin 73. At its lower end the pin 73 is connected through a universal joint with one arm 75 of a lever pivotally mounted, by means of a sleeve 76 integral with the lever, on a stud 77 carried by a lug 78 extending upwardly from the plate member 16. The universal joint connecting the pin 73 with the arm 75 comprises a socket element 73b at the lower end of the pin which receives a ball ele-

ment 73c carried by the arm. The ball element may be positioned in either of a plurality of openings 75d in a bent-over branch of the arm 75. This permits the ball element to be mounted in the position best suited for the particular adjustment of the power unit on the member 16. A downwardly extending arm 79 of the lever is connected by means of a rod or link 80 with a piston rod 81 (Fig. 3) of a reciprocating pump 82. The latter may suitably be of the type disclosed in the patent to Smith, No. 2,430,370, granted November 4, 1947, and may be arranged to transfer lubricant from different points within the sewing machine frame to suitable reservoirs for distribution to the various parts requiring lubrication, all as fully set forth in said Smith patent.

Turning now to the rod 63 connected with the treadle 56, this, as best shown in Figs. 1 and 2, is connected at its upper end with an arm 83. Rod 63 passes through an opening in the arm 83 and carries a collar 84 above said arm having a spherical lower end arranged to engage the upper surface of the arm. A sleeve 85 surrounding the rod 63 engages the under surface of the arm 83 and is held in such position by a collar 86 secured to the rod. A slight clearance is provided for the arm 83 between the collar 84 and sleeve 85 to permit the necessary relative movement between these parts. A spring 87 connected with the outer end of the arm 83 and with the collar 86 serves to take up the play between the parts and holds the arm against the upper end of the sleeve 85.

Arm 83 is integral with, or otherwise connected with, a sleeve 88 secured by a set screw or the like to a rock shaft 89 journaled in bearing lugs 90 and 91 (Figs. 1 and 3) extending upwardly from the upper surface of the support member 14. Another arm 92 (Figs. 2 and 3) extending rearwardly from the sleeve 88 has a spring 93 connected with its outer end, said spring having its opposite end attached to a small bracket 94 secured to the support member 14. This arrangement is such that the shaft 89 is urged in a counterclockwise direction (Fig. 2) and tends to urge the rod 63 upwardly. Upon depression of the treadle 56 and downward movement of the rod 63, shaft 89 is rocked in a clockwise direction (Fig. 2). This causes lifting of the presser bar of the sewing machine through connections of the type disclosed in the application of Norman V. Christensen and George Sauer, Serial No. 704,822, filed October 22, 1946, now Patent No. 2,511,047, dated June 13, 1950. These connections include an arm 95 secured to shaft 89 adjacent bearing lug 91. Arm 95 is connected by a link 96 with an arm 97 mounted on the frame of the sewing machine and which is, in turn, connected by a link 98 with a presser bar lifting arm 99 mounted on the side of the needle head of the sewing machine.

It will be understood that the lever 97 in the foregoing linkage performs the same function as the bell crank lever 53 in the construction of the Smith patent above mentioned and the operation of the linkage is such as to bring about lifting of the presser bar 100, upon the depression of the treadle 56, in opposition to the spring 101 (Figs. 1 and 3).

A cover is preferably provided for the power unit, this being best illustrated in Figs. 9, 10 and 11. The cover is indicated generally at 102 and it may comprise three sheet metal sections 103, 104 and 105. The section 103 forms the top and two sides of the cover and sections 104 and 105

form the two ends, these three sections being welded together along the overlapping edges indicated in Figs. 9 and 10. For retaining the cover it is suitably provided with three foot members formed by bracket elements 106 welded or otherwise secured to the inner surface of the cover at the three points shown, each bracket element having secured to it a vertically disposed pin 107. The latter may be welded or otherwise secured to the side of the bracket and projects a suitable distance below the lower edge of the bracket and the lower edge of the cover. Pins 107 are adapted to enter openings 108 provided in the support member 14, as shown in Fig. 3. A small rubber sleeve 109 is preferably applied to the projecting end of each of the pins 107, as shown in Fig. 11, to prevent the transmission of vibrations from the support member to the cover. These rubber sleeves, moreover, provide adequate friction for firmly retaining the cover, so that no screws or bolts are required. An opening 110, provided in one wall of the member 103 of the cover and in the adjacent portion of the end section 105, allows for the passage of the driving belt 42 and also portions of the connections from the treadles to the sewing machine. An opening 111 provided centrally through the end wall of the section 105 permits the application and removal of the cover over the hand wheel 47. The lower edge of section 105 is also cut away sufficiently to accommodate the adjacent portion of the member 16.

It will be understood that the sewing unit may be provided with a portion 112 extending beyond the wall of the cover 102 (Fig. 9) and this may carry a post 113 for supporting a thread stand. If desired, needle cooling means of the type disclosed in the Christensen et al. application Serial No. 704,822 may be provided and for this purpose the support member 14 is provided with an extension 114 having a horizontally disposed opening 115 therethrough. For further details as to the construction and mounting of the needle cooling means, reference may be had to the Christensen et al. application hereinabove mentioned.

While an illustrative embodiment of the invention has been disclosed in considerable detail, it will be understood that various changes may be made in the construction and arrangement of the several parts without departing from the general principles and scope of the invention.

What I claim is:

1. In a pedestal mounting for a sewing machine and its driving means which comprises a base, a column extending upwardly from said base, and a laterally extending support member mounted on said column adjacent its upper end, the combination of a rigid plate-like member secured directly to the upper surface of said support member, said plate-like member being rigid throughout, vibration absorbing means interposed between said members, and means for securing the sewing machine and its driving means directly to said plate-like member.

2. In a pedestal mounting for a sewing machine and its driving means which comprises a base, a column extending upwardly from said base, and a laterally extending support member mounted on said column adjacent its upper end, the combination of a rigid plate-like member mounted on the upper surface of said support member, said plate-like member being of integral construction and rigid throughout, a plurality of bolt means comprising screw threaded elements secured at their opposite ends to said members and having vibration absorbing elements interposed between said

members, said vibration absorbing elements comprising small pads surrounding said screw threaded elements and serving to maintain said members in spaced relation, and means for securing the sewing machine and its driving means directly to said plate-like member.

3. In a pedestal mounting for a sewing machine and its driving means which comprises a base, a column extending upwardly from said base, and a laterally extending support member mounted on said column adjacent its upper end, the combination of a rigid plate-like member secured to the upper surface of said support member, vibration absorbing means interposed between said members and arranged to prevent transmission of vibrations there-between, said plate-like member having a portion projecting beyond the edge of said support member, means for securing the sewing machine to the projecting portion of said plate-like member, and means for securing the driving means to the upper surface of said plate-like member.

4. In a pedestal mounting for a sewing machine and its driving means which comprises a base, a column extending upwardly from said base, and a laterally extending support member mounted on said column adjacent its upper end, the combination of a rigid plate-like member secured to the upper surface of said support member, vibration absorbing means interposed between said members and arranged to prevent transmission of vibrations there-between, said plate-like member having a portion projecting beyond the edge of said support member and extending downwardly over the edge thereof, the plate-like member being substantially thickened at and adjacent said projecting portion, means for securing the sewing machine to the downwardly extending part of said portion, and means for securing the driving means to the upper surface of a non-thickened portion of said plate-like member.

5. In a pedestal mounting for a sewing machine and its driving means which comprises a base, a column extending upwardly from said base, and a laterally extending support member mounted on said column adjacent its upper end, the combination of a rigid plate-like member disposed over the upper surface of said support member, vibration absorbing means interposed between said members, said plate-like member being of substantially uniform thickness in a portion thereof overlying said support member and being thickened in both directions from the median plane thereof in a second portion, a pair of bolts carried by each of said vibration absorbing means in spaced relation for securing said members together said second portion projecting beyond the edge of said support member and having a part extending downwardly over said edge, means for securing the sewing machine to said part, and means for securing the driving means to the upper surface of said first mentioned portion thereof.

6. In a pedestal mounting for a sewing machine and its driving means which comprises a base, a column extending upwardly from said base, and a laterally extending support member mounted on said column adjacent its upper end, the combination of an integral plate-like member rigid throughout disposed over the upper surface of said support member, said members having a plurality of spaced recesses in their opposed faces, each recess in one member being alined with a recess in the other, vibration absorbing means seated in each alined pair of said recesses serving to retain the opposed surfaces of said members in

spaced relation, a pair of bolts carried by each of said vibration absorbing means in spaced relation for securing said members together and means for securing the sewing machine and its driving means directly to said plate-like member.

7. In a sewing unit comprising a pedestal having a floor engaging base, a column extending upwardly from said base and a horizontally disposed support member at the upper end of said column, the combination of a carrying member extending over said support member and having a portion projecting beyond the edge thereof, vibration absorbing connections for securing said members firmly together, yieldable vibration absorbing means associated with said connections and interposed between said members for maintaining the same in spaced relation, a sewing machine secured to the projecting portion of said carrying member and having a work support below said support member, motor drive means connected with said sewing machine for operating the same, said motor drive means being mounted on said carrying member over said support member, and means for securing said motor drive means to said carrying member.

8. In a sewing unit comprising a pedestal having a floor engaging base, a column extending upwardly from said base and a horizontally disposed support member at the upper end of said column, the combination of a carrying member extending over said support member and having a portion projecting beyond the edge thereof, vibration absorbing connections for securing said members firmly together, yieldable vibration absorbing means associated with said connections and interposed between said members for maintaining the same in spaced relation, a sewing machine rigidly secured to the projecting portion of said carrying member and having a work support below said support member, motor drive means mounted on said carrying member over said support, said drive means and said sewing machine having pulleys disposed in the same vertical plane, a belt connecting said pulleys, and vibration absorbing means for adjustably securing said drive means to said carrying member and enabling relative adjustment thereof to vary the tension of said belt.

9. In a sewing unit comprising a pedestal having a floor engaging base, a column extending upwardly from said base and a horizontally disposed support member at the upper end of said column, the combination of a carrying member extending over said support member and having a portion projecting beyond the edge thereof, vibration absorbing connections for securing said members firmly together, yieldable vibration absorbing means associated with said connections and interposed between said members for maintaining the same in spaced relation, a sewing machine secured to the projecting portion of said carrying member and having a work support below said support member, motor drive means connected with said sewing machine for

operating the same, said motor drive means being mounted on said carrying member over said support member, means for securing said motor drive means to said carrying member, treadle means mounted on said base, and yielding connections from said treadle means to said sewing machine and to said motor drive.

10. In a sewing unit comprising a pedestal having a floor engaging base, a column extending upwardly from said base and a horizontally disposed support member at the upper end of said column, the combination of a carrying member extending over said support member and having a portion projecting beyond the edge thereof, vibration absorbing connections for securing said members firmly together, yieldable vibration absorbing means associated with said connections and interposed between said members for maintaining the same in spaced relation, a sewing machine secured to the projecting portion of said carrying member and having a work support below said support member, motor drive means mounted on said carrying member over said support, said drive means and said sewing machine having pulleys disposed in the same vertical plane, a belt connecting said pulleys, means for adjustably securing said drive means to said carrying member and enabling relative adjustment thereof to vary the tension of said belt, treadle means mounted on said base, and yielding connections from said treadle means to said motor drive means and said sewing machine including a rock member mounted on said drive means and a rock shaft carried by said support member.

15 30 35 40 45 50 55

11. In a sewing unit comprising a supporting structure having a horizontally disposed support member, the combination of a carrying member extending over said support member and having a portion projecting beyond the edge thereof, a plurality of bolt members for securing said support member and said carrying member firmly together, each of said bolt members comprising a pair of screw threaded elements having enlarged heads and a coupling element formed of yieldable vibration absorbing material for retaining said screw threaded elements in assembled but spaced relation, said vibration elements absorbing material being positioned between said support member and said carrying member and keeping the same in spaced relation, a sewing machine secured to the projecting portion of said carrying member, a power unit carried by one of said members and connected with said sewing machine for driving the same.

JOHN G. ATTWOOD.
